UNITED STATES PATENT OFFICE.

MARCEL EUGÈNE ESBRAN, OF PARIS, FRANCE, ASSIGNOR TO THE FIRM TIRAGE ET VENTILATION MECANIQUES, OF PARIS, FRANCE.

HEAT EXCHANGER.

Application filed October 21, 1924, Serial No. 745,023, and in France October 30, 1923.

This invention relates to a device for exchanging heat between fluids at different temperatures, circulating, each in its own conduit and refers more particularly to the heating of the air supply of furnace and like grates by means of exhaust gases.

The object in view is to effect said exchange otherwise than by conduction through the walls of the conduits, the fluids circulating each in a special fixed, non-deformable and continuous conduit, which is the sole way of preventing any mixing. Secondly, the existence of common walls enables an exchange of heat to be obtained which supplements that effected by means of the apparatus.

This object is accomplished by means of the hereinafter described device, which is characterized by a rotating member shaped and actuated in such a way that its surface is bathed simultaneously in all the fluids, by penetrating into their conduits through slits which it keeps obstructed the whole time.

In the accompanying diagrammatic drawings, Figure 1 represents a sectional elevation on the line 1—1, Figure 3 of a simple type of air heater, which is given by way of example, Figure 2 is a sectional side elevation of the device shown in Figure 1, and Figure 3 is a sectional plan on the line 3—3, Figure 1.

Figures 4 and 5 show, in the same positions as in Figures 1 and 2, a modification of the wall which is common to the conduits.

Figures 6 and 7 are similar views of another modification of said wall.

In the embodiment shown in Figures 1, 2 and 3, the heat transmitting member is a rotating body and is composed of plain discs *h* threaded on a shaft *f* supported by bearings *g*. Two conduits, *a* for cold air and *b* for exhaust gases, are of rectangular section in this instance and have a common wall *c*, and they are provided with an enlargement *d* in which the movable member is housed. The wall *c* is duplicated, round the shaft *f*, by a partition *e*, in such a way as to clear and enclose said shaft. Slits *i* are provided in the partitions *c* and *e* for the passage of the discs *h*, tongues *j* being left between the slits.

It will be evident that when the movable member revolves, whether continuously or not, it will always occupy the same space, will keep the slits *i* obstructed all the time,

and will convey heat from one conduit to the other.

It is known that the coefficient of heat transmission between fluids and solids, such as the discs *h*, increases with their relative velocity. Whatever the velocity of the fluids in the two conduits, it is always possible to increase their velocity in relation to the movable member to an unlimited extent by increasing the rotational velocity of this latter. Hence it is possible, with a small apparatus, to obtain considerable exchanges of heat without the velocity of the fluids in their conduits being high.

The shaft *f* being arranged transversely of the path of the fluids, it is possible, without increasing its operative portion lengthwise, to mount the bearings *g* outside, so as to facilitate cooling and inspection.

Any desired degree of tightness at the slits *i* may be obtained by providing the edges of said slits in the walls of the conduits either with members making a light frictional contact with the discs *h*, or by providing expansion chambers, of the baffle or labyrinth type, without contact. By providing them with scrapers of any known type (not shown) the cleaning of the movable member can be effected automatically.

Finally, any unavoidable leakages may be rendered of no importance by causing them to return to one of the conduits, as the result of a difference in pressure. For example, if it be desired to have the air very pure, with a view to using it for drying, all that is needed is to adjust the fans in such a way that the pressure in the air section of the apparatus is higher than that in the gas section. The gases will contain a little air, but the air will be free from gas.

The tongues *j* left between two consecutive slits *i* in the wall *c* may, instead of surrounding the shaft *f* as in Figures 1, 2 and 3, simply clear it, as in Figures 4 and 5, or again may be cut off to allow it to pass, as in Figures 6 and 7.

The air heater described above has been given merely by way of example.

What I claim is:

1. A heat exchanging device comprising 105 conduits for two different fluids separated by a common wall having a plurality of slits therein, a heat transmitting member formed of a plurality of rotatable bodies passing through said slits and having a common axis 110

arranged perpendicularly to the direction of flow of both fluids, and means for causing said bodies to rotate whereby they pass alternately from one fluid to the other.

- 5 2. A heat exchanging device comprising conduits for two different fluids separated by a common wall having a plurality of slits therein, and a heat transmitting member consisting of a rotatable axle provided with 10 a number of disks passing through said slits, the axle being arranged perpendicularly to the direction of flow of both fluids.
- 10 3. A heat exchanging device including a plurality of conduits adapted to confine two

fluids at different temperatures and having 15 a common wall between the same provided with a number of slits, a rotatable axle extending through opposite walls of said conduits, bearings for the axle situated exteriorly of the conduits, and disks fixed on 20 the axle and extending through the slits, whereby when the axle is rotated the disks will revolve through said slits from one conduit to the other.

In testimony whereof I hereunto affix my 25 signature.

MARCEL EUGÈNE ESBAN.
